ELECTROLYTIC CELL.

979,485.

Specification of Letters Patent. Patented Dec. 27, 1910.

Application filed September 27, 1910. Serial No. 584,067.

To all whom it may concern:

Be it known that we, DERICK S. HARTSHORN and ALAN A. CLAFLIN, citizens of the United States, and residents, respectively, of 5 Boston, in the county of Suffolk, and Medford, in the county of Middlesex, both in the State of Massachusetts, have invented new and useful Improvements in Electrolytic Cells, of which the following is a specification.

The primary object of our present invention is to facilitate the escape of a gas liberated by electrolysis and thereby to prevent such gas from polarizing the electrode at 15 which it appears and from inducing secondary reactions in the electrolyte by retention therein after its liberation.

Our invention may be exemplified by an electrolytic cell arranged for the conversion 20 of potassium chlorid into potassium chlorate. For this purpose we construct an apparatus such as is illustrated in the accompanying drawings, wherein—

Figure 1 represents a transverse vertical 25 section of one form of cell; Fig. 2 a longitudinal vertical section of the same cell taken in planes on lines 2—2 of Fig. 1; Fig. 3 a transverse vertical section of an alternative form of cell; Fig. 4 a longitudinal 30 vertical section of the latter cell taken between the two pairs of sprocket-wheels; and Fig. 5 a detail belonging thereto.

In the apparatus represented by Fig. 1 and Fig. 2, the main body *a* of the cell is a 35 rectangular vessel made of or lined with a concrete of hydraulic cement or other chemically resistant material; and at the top edge of one of its longitudinal sides it has a lateral extension *b* curving outward and upward through about a quadrant of a cylindrical segment, to which geometrical shape it conforms in its lower portions but flares away therefrom somewhat at its upper parts. The other longitudinal side of the main body 40 of the vessel is made higher than the lower edge of the lateral extension opposite thereto and from the top of this higher side the upper edges of the ends of the vessel are extended across the ends of the lateral extension to meet the upper edge of the same and thus to inclose the space otherwise bounded by the cylindrical quadrant.

The lower portion of the interior of the lateral extension of the cell which there conforms to a cylindrical segment is covered 45

with a metal plate *c* of corresponding shape, either consisting entirely of platinum or having its exposed surface plated with platinum and its edges turned backward and embedded in the cement concrete to prevent corrosion at the junction of the platinum with the cheaper metal upon which it is plated for economic reasons. This platinum plate constitutes the anode of the electrolytic cell. Upon the upper edges of the 50 ends of the body of the cell, above the lower edge of its lateral extension, are mounted bearings for a shaft *d* extending lengthwise of the cell and having its axis concentric with the cylindrical segment surface of the 55 platinum anode. This shaft *d* is made of copper and it carries a cylindrical cage symmetrical thereto, also made of copper and having the circumferential periphery of its drum composed of a series of parallel copper bars *e*, *e*, likewise parallel to the shaft and preferably so shaped in cross section as to have the outermost surface of each as 60 nearly as practicable a short segment of a cylinder concentric to the axis of the shaft 65 around which it is made to revolve; but if sufficiently numerous these bars can be rectangular in cross-section. A convenient mode of supporting them is by annular rims 70 *f*, *f*, at the outer ends of spokes *g*, *g*, extending radially from the shaft. These peripheral bars of the cylindrical cage constitute the cathode of the electrolytic cell when 75 brought into close proximity to the platinum anode; and for the most effective work 80 the outermost surface of each when opposed to the exposed surface of such anode should be about one sixteenth of an inch therefrom. A belt-pulley *h* upon one end of the shaft *d* 85 serves to rotate the cage and to revolve the 90 series of cathode-bars in front of the anode in the direction indicated by an arrow. A suitable cable *i* containing an insulated conductor which has its end securely soldered to the back plate of the anode and leads from 95 the positive pole of an electric generator 100 serves to supply the electric current to the electrolytic cell; and another similar conductor *j* leading from the negative pole of the same generator and terminating in an 105 intimate contact *k* with one of the metal journal-boxes of the shaft *d*, serves to complete the electric circuit, when the space between the opposed electrodes is bridged over by the liquid electrolyte.

22

The best position for the stationary electrode is such as to locate the greater part of its area where the rise of its curvature above a horizontal plane has the lesser increments, so that when the level of the liquid electrolyte in the electrolytic cell reaches high enough to enable the lower part of the circumferential periphery of the rotary electrode to dip below its surface a considerable portion of the stationary electrode will be covered by such liquid; although, of course, as soon as the rotary electrode is set in motion as intended in a direction from the bottom toward the top of the cylindrical lateral extension of the electrolytic cell, it will sweep the liquid electrolyte into which it dips, along with it so as to cover an additional surface of the stationary electrode if this extends above the initial level to which the cell was originally filled, and will thus proportionately increase the area of electrolytic action.

In order to prevent undue radiation of heat from the external walls of the electrolytic vessel, they are covered with wooden lagging m , m_1 , or other thermally non-conducting material; and for the like purpose the top of the vessel is provided with a heat-obstructing cover which may be regulated in size to suit the exigencies of the weather; while independently of such cover, or as a lining to a portion of it, a sheet-metal hood is placed over the revolving cage to confine the spattering of the liquid operated upon.

The method of procedure with this apparatus and its mode of operation when employed for converting potassium chlorid into potassium chlorate are as follows: An aqueous solution of potassium chlorid, preferably standing at about 18° Baumé, and constituting the electrolyte, is at the outset of the process heated to about 140° Fahrenheit, and for the best results should be maintained as nearly as may be at that temperature during the progress of the electrolysis. The electrolytic cell hereinbefore described is filled with such solution up to a level at which the circumferential periphery of the cylindrical cage will dip just below its surface; and any diminution of the volume of liquid in the course of the operation is to be compensated for, from time to time, by the addition of a suitable quantity of water. The electric current is then turned on and the cylindrical cage set into rotation in a direction which causes its cathode copper bars to sweep the electrolyte solution up the incline of the anode platinum plate and there subject it to electrolysis in a thin liquid sheet. By this means the hydrogen liberated at the surfaces of the cathode-bars is assisted to effect an immediate escape, first, by the rapid travel of the bars themselves out of the liquid electrolyte carrying with them the hydrogen bubbles adhering there-

to; and second, by the agitation of the thin sheet of liquid itself between the electrodes, caused by the swift passage of the bars through it, and the consequent breaking up of its surface tension which would otherwise tend to retard the escape of such hydrogen bubbles as were held in suspension. In order to prevent polarization of the cathodes by any persistent adhesion of hydrogen bubbles thereto, a stationary brush n may be mounted above the revolving cage in such position as to wipe the surfaces of the peripheral bars. The heat evolved by this electrolysis is under ordinary atmospheric conditions sufficient to maintain the temperature of the electrolyte at the desired point of about 140° Fahrenheit, in such an electrolytic cell as is hereinabove described when provided with the means specified for preventing undue refrigeration. Indeed, it will sometimes happen that the contents of the cell become too hot and need to be allowed to cool off by removing part or all of the cover which may be made in separate divisions for that purpose; and on the other hand the exposure of the apparatus to the effects of too severe winter weather may render expedient the application of extraneous heat such as would be supplied by a steam coil within the body of the vessel containing the electrolyte. If the temperature of the potassium chlorid solution falls below 95° Fahrenheit the obtainment of potassium chlorate therefrom by this electrolytic process is seriously interfered with by the formation of hypochlorites; and on the other hand, the efficiency of the process is greatly diminished by an increase of temperature above 180° Fahrenheit.

For economic working the capacity of the electrolytic cell should be sufficient to enable the electrolysis to go on uninterruptedly for a considerable time, say, an entire day, without bringing the solution too near the point of saturation with potassium chlorate; for, its increase in quantity within the potassium chlorid solution proportionately diminishes the effectiveness of the electrolysis in producing the resulting conversion. At the conclusion of the period set for continuous working, the solution operated upon is allowed to cool; whereupon the potassium chlorate precipitates in crystals and the depleted liquid is then drawn off to be enriched with more potassium chlorid ready for further subjection to the same process.

The conversion of potassium chlorid into potassium chlorate by electrolysis is old, and the chemical transformations by which this result is brought about are well understood in the art. We have described this process as far as requisite for exemplifying the peculiar construction and mode of operation of our electrolytic cell, which is adapted for use in conducting other electrolysis wherein

a gas is liberated at one of the electrodes and needs to be eliminated with despatch in such manner as to avoid polarization of the electrode at which it appears and to prevent secondary reactions resulting from its further detention within the electrolyte solution.

The fundamental principle of our invention when embodied in the most effective mode, as exemplified in the electrolytic cell hereinabove described, is that one of the electrodes shall consist of an extended series of constituent members which, in continuous succession, are made to travel into and out of the liquid electrolyte; are brought into operative position in front of the other electrode of opposite electric polarity, only when their working faces are near to the surface of the liquid electrolyte in which they are immersed; and are conveyed thence directly out of the liquid electrolyte; or in other words, that each component of such traveling electrode shall arrive at its operative position opposite and in suitable proximity to the other electrode, with its electrically active face immersed only just far enough below the surface of the liquid electrolyte to enable this latter to fill the narrow space between the two opposed electrodes, and shall by its onward movement agitate the surface of the liquid electrolyte and without lingering, pass above the same. Obviously, however, the traveling compound electrode need not invariably constitute such a cyclic series of bars as to form the circumferential periphery of a rotary cylindrical cage, but might, for example, be arranged like the components of an endless slatted apron running over and moved by suitable rotative carriers such as sprocket wheels to bring the several electrode members of the series in continuous succession into a position facing the oppositely electrified electrode and in close proximity thereto just beneath the surface of the liquid electrolyte and thence directly above the same; in which case, of course, the shape of the face of the stationary electrode as well as its position would have to conform and be parallel to the path of movement of the components of the traveling electrode.

Such a modified form of apparatus assumed to be put to the same uses as that already described in connection with Figs. 1 and 2, is illustrated by Figs. 3, 4 and 5 of the drawings, wherein the body a' of the cell is a rectangular vessel made of or lined with a concrete of hydraulic cement or other chemically resistant material and externally protected by wooden lagging m' , m'' or other non-conductor of heat. Within this cell is a flat horizontal table b' which with its supports are made of chemically resistant material, and which is covered with a metal plate c' of corresponding shape either consisting entirely of platinum or having its exposed

surface plated with platinum and its edges turned backward and embedded in cement concrete to prevent corrosion of the cheaper metal backing. Upon the upper edges of the body of the cell are mounted bearings for shafts d' , d'' , extending lengthwise of the cell and each carrying a pair of sprocket wheels g' , g'' . Encompassing these two pairs of sprocket wheels is an endless slatted apron consisting of a continuous series of bars e' , e'' , supported at their ends in sockets f' , f'' , which are connected together by alternately fixed and pivoted links in such manner that each fixed link o rigidly holds a pair of sockets in such position that its two bars are kept transversely parallel to such fixed link, while each pivoted link p flexibly joins two consecutive pairs of rigidly held sockets. The series of links forms an endless chain which while flexible as a whole, maintains the bars of the slatted apron flatwise to their path of travel. The sockets thus chained together are spaced apart at distances just right to permit the sprockets of the sprocket-wheels to fit between them. The shaft of one of the pairs of sprocket-wheels is to be provided with a driving pulley outside of its bearing, and the shaft of the other pair of sprocket-wheels should have its journal-boxes adjustable toward and from those of the driving shaft to enable the endless slatted apron to be made taut enough to keep it from sagging materially between its rotating supports. These contrivances are too obvious to need delineation in the drawings. The bars of the endless slatted apron constitute the cathode of this form of electrolytic cell. They are of copper and so also are their sockets and interconnecting links, as well as the sprocket-wheels, their shafts and journal bearings. A suitable cable i' containing an insulated conductor which has its end securely soldered to the back-plate of the anode and leads from the positive pole of an electric generator, through passages provided for the purpose in the table and its supports, serves to supply the electric current to the electrolytic cell; and another similar conductor j' leading from the negative pole of the same generator and terminating in an intimate contact k' with one of the metal journal-boxes of the driving shaft d' serves to complete the electric circuit, when the space between the bars on the bottom of the endless slatted apron and the platinum plate on the top of the table is bridged over by the liquid electrolyte.

Manifestly, the closer together the bars of the traveling electrodes are, the greater will be the relative area presented for electrolytic activity, but on the other hand too close proximity of these to each other may diminish the facility of escape of the liberated gas between them; and in the particular case of use for converting potassium chlorid

into potassium chlorate, the fact that it is desirable to have the total area of the electrically active faces of the cathode only about one half of the area of the opposed anode, will serve to determine the distance between the cathode-bars. For other uses, however, it may well happen that a relatively greater electrically active area of the traveling electrode will be needed, sufficient even to render it expedient, when employing the form of apparatus wherein the traveling electrode is a rotating cylinder, not to construct its circumferential periphery of separated components. Furthermore, except under such conditions as are presented in the conversion of potassium chlorid into potassium chlorate, the traveling compound electrode in either form of apparatus hereinabove described need not be the cathode of the electrolytic cell. It might constitute the anode, if the electro-chemical conditions caused the gas which required elimination to be liberated at that electrode. And in all cases, of course, the constitution of the electrodes themselves will have to be suited to the electro-chemical conditions under which they are to operate. Hence, with these explanations it will be seen that our electrolytic cell is adapted to be used for the oxidation by electrolysis, not only of chlorids into chlorates, but also of chromic salts into chromates, of arsenious salts into arsenates, of ferrous salts into ferric salts, and to effect in like manner many other kindred transformations; or even the converse of such reactions by reversing the direction of the electric current to perform reductions of which an example would be furnished in the conversation of nitro-benzol into anilin by liberating oxygen instead of hydrogen. Finally it is to be remarked that the nearer the working faces of the traveling electrode remain to the surface of the liquid electrolyte as they pass along through the latter with a rapidity of movement tending to agitate such surface, the more thoroughly will the surface tension of the liquid electrolyte be broken up, and the more effectually will the escape of the gas there liberated by electrolysis be facilitated; so that the efficiency of the apparatus herein described for the purpose of this invention, would diminish in proportion to the depth of immersion of the traveling electrode and would practically disappear as soon as the gas liberated at the working faces of the traveling electrode, was by the movement of the latter stirred into the mass of the liquid electrolyte and diffused therein to produce secondary reactions, instead of having its escape therefrom promoted by liberation in close proximity to an agitated surface.

We claim:

63 1. In an electrolytic cell, two electrodes

of opposite electric polarity, one of which is composed of a series of constituent members and is provided with means whereby these members, in continuous succession, are made to dip into the liquid electrolyte from above its level, to travel through the liquid electrolyte only just beneath the surface thereof with a velocity tending to agitate such surface, and thence to pass directly out of the liquid electrolyte; while the other electrode is located farther below the surface of the liquid electrolyte, opposite and in suitable proximity to the traveling electrode where the latter occupies its immersed position.

2. In an electrolytic cell, a movable electrode composed of a series of constituent members and provided with means whereby these members, in continuous succession, are made to dip into the liquid electrolyte from above its level, to travel through the liquid electrolyte only just beneath the surface thereof with a velocity tending to agitate such surface, and thence to pass directly out of the liquid electrolyte, in combination with a stationary electrode of opposite electric polarity, located farther below the surface of the liquid electrolyte in a position opposed and in suitable proximity to an immersed portion of the movable electrode.

3. In an electrolytic cell, a movable electrode composed of a series of constituent members and provided with means whereby these members, in continuous succession, are made to dip into the liquid electrolyte from above its level, to travel through the liquid electrolyte only just beneath the surface thereof with a velocity tending to agitate such surface, and thence to pass directly out of the liquid electrolyte, in combination with a stationary electrode plate of opposite electric polarity, located farther below the surface of the liquid electrolyte, in a position parallel to the path of the immersed portion of the movable electrode and in suitable proximity thereto.

4. In an electrolytic cell, a movable electrode composed of a cyclic series of interconnected parallel bars supported partly above and partly below, the level of the liquid electrolyte and provided with rotative means whereby they are made to travel in continuous succession in an endless course transverse to their length into and out of the liquid electrolyte, but only to become immersed therein just beneath its surface and to move through the same with a velocity tending to agitate such surface, in combination with a stationary electrode plate of opposite electric polarity located farther below the surface of the liquid electrolyte in a position parallel to the path of the immersed portion of the movable electrode and in suitable proximity thereto.

5. In an electrolytic cell, an electrode con-

sisting of a rotary cylinder mounted on a horizontal axis, with its circumferential periphery mostly above, but having a lower segment dipping into and only just below the surface of the liquid electrolyte, in combination with a stationary electrode concentric to the segment of the rotary cylindrical electrode thus immersed, and located opposite and in suitable proximity thereto beneath the surface of the liquid electrolyte.

6. In an electrolytic cell, an electrode consisting of a rotary cylindrical cage mounted on a horizontal axis and having its circumferential periphery composed of a continuous series of separate longitudinal bars, with most of this circumferential periphery above but a lower segment thereof dipping into and only just below the surface of the liquid electrolyte, in combination with a stationary electrode concentric to such immersed segment of the rotary cylindrical electrode and located opposite and in suitable proximity thereto beneath the surface of the liquid electrolyte.

7. An electrolytic cell, comprising a lateral extension curving outward and upward from the top of one of the sides of its main body and inclosed between its correspondingly extended ends; a stationary electrode-plate supported upon the inside of this curved extension and shaped to the segment of a cylinder; a rotary electrode consisting of a cylindrical cage mounted on a horizontal axis concentric to the curvature of the stationary electrode-plate and so dimensioned that its circumferential periphery composed of a continuous series of longitudinal bars is brought into suitable proximity to such stationary electrode-plate; and

such an arrangement of these constituents that the liquid electrolyte when at its intended normal level in the electrolytic cell will cover the face of the stationary electrode in whole or in part and will simultaneously immerse just below its surface more or less of the circumferential periphery of the rotary electrode where this latter is directly opposed to the face of the stationary electrode thus covered.

8. An electrolytic cell, comprising a lateral extension curving outward and upward from the top of one of the sides of its main body and inclosed between its correspondingly extended ends; a stationary anode-plate supported upon the inside of this curved extension and shaped to the segment of a cylinder; a rotary cathode consisting of a cylindrical cage mounted on a horizontal axis concentric to the curvature of the stationary anode-plate and so dimensioned that its circumferential periphery composed of a continuous series of longitudinal bars is brought into close proximity to such stationary anode-plate; and such an arrangement of these constituents that the liquid electrolyte when at its intended normal level in the electrolytic cell will cover the face of the stationary anode in whole or in part, and will simultaneously immerse just below its surface more or less of the circumferential periphery of the rotary cathode where this latter is directly opposed to the face of the stationary anode-plate thus covered.
